UNITED STATES PATENT OFFICE.

IGNATIUS G. POSPYHALA, OF SPRING VALLEY, ILLINOIS.

RAILROAD-TRACK SWITCH.

1,352,988.

Specification of Letters Patent. Patented Sept. 14, 1920.

Application filed April 12, 1919. Serial No. 289,737.

To all whom it may concern:

Be it known that I, IGNATIUS G. POSPYHALA, a citizen of the United States, and a resident of Spring Valley, Illinois, have 5 invented a certain new and useful Improvement in Railroad-Track Switches, of which the following is a specification.

This invention relates to railroad track switches, and more particularly to those 10 which are used for tracks on which electric motors are employed to haul small cars, such as those employed in the hauling of coal, or for any other desired purpose.

Generally stated, the object of the invention 15 is to provide an improved construction and arrangement whereby a flying switch may be made automatically, without the necessity of manually controlling the switch mechanism, the latter being controlled automatically by means carried on the motor, or 20 on some portion of the rolling stock, so that the motor or locomotive will travel straight ahead and the cars behind will be shunted off onto a side track, or onto another track, 25 in the well known manner, and without the necessity of any manual control of the switch.

It is also an object to provide certain details and features of construction and combinations tending to increase the general 30 efficiency and the desirability of an automatically controlled track switch of this particular character.

To these and other useful ends, the invention 35 consists in matters hereinafter set forth and claimed.

In the accompanying drawings—

Figure 1 is a plan of a section of the track 40 having a switch mechanism embodying the principles of the invention.

Fig. 2 is a side elevation of said track section and switch mechanism, showing a portion of the motor upon which the means are mounted to automatically control the 45 switch mechanism.

Fig. 3 is an enlarged cross section of the track, on line 3—3 in Fig. 1, showing the switch mechanism in elevation, and showing the position of the motor and the means 50 thereon to automatically control said mechanism.

Fig. 4 is a detail of a portion of the track switch mechanism.

Fig. 5 is a similar view.

Fig. 6 is a view similar to the right hand 55 portion of Fig. 3, but showing another form of the invention.

Fig. 7 is an enlarged plan of a part of the construction shown in Fig. 1.

As thus illustrated, the invention comprises 60 a main track 1, 2, and 3, laid on ties or sleepers 4 of any suitable character, and fastened thereto. The switch points 5 and 6 are of any suitable or ordinary character, being secured at 7 and at 8 in a manner 65 which will permit them to swing laterally. The point 5 leads to the side track rail 9, and the point 6, when open, permits the wheels of the rolling stock to travel from the rail 2 onto the side track rail 10, the 70 latter and the rail 9 constituting the stationary side track which is secured to the ties in any suitable manner. The switch points 5 and 6 are connected together by a rod 11 which is pivotally connected with one end 75 of a lever 12 which is fulcrumed at 13 on the plate 14 secured to the tie, whereby this lever swings in a horizontal plane to open and close the switch. A roller 15 is supported 80 on the upper side of the other end portion of said lever, in position to be engaged by the cam plate 16 secured to the bottom of the motor 17 which latter may be of any suitable character. It will be seen that the cam plate 16 is disposed at such an 85 angle that it will strike the roller 15, after the wheels of the motor have passed the switch, traveling to the right in Fig. 1, thus automatically closing the switch.

The outer end of the rod 11 is connected 90 by rods 18 and 19, which are adjustably connected together, by a turn buckle 20, with the weight 21 at the outer end thereof. The rod 18, it will be seen, is pivotally connected at 22 with the outer end of the rod 95 11, and with this arrangement the weight 21 can move up and down. The rod 19 has a depending portion 23, and said rod rests on a grooved wheel 24 mounted on one of the ties. A hand lever 25, suitably fulcrumed 100 at 26, is connected with the rod 19, whereby the switch mechanism can be manually con-

trolled when such is necessary or desirable. With this arrangement, the depression or depending portion 23 will tend to hold the switch either open or closed, depending upon 5 whether it is inside of the wheel 24 or at the outer side thereof, inasmuch as in order to move the switch from one position to the other, the portion 23 must ride over the wheel 24, and this is opposed by the weight 10 21 at the outer end of the rod.

Assuming that the motor and its train of cars is approaching the switch from the left in Fig. 1, the operation is as follows: The wheels of the motor will pass the switch and 15 travel on the rails 1 and 3, just to the right of the places 7 and 8 where the switch points are movably secured to one of the ties. At about this time, the plate 16 will strike the roller 15 and will swing the switch point 5 20 tightly against the rail 1, and the point 6 a distance away from the rail 2, thereby closing the switch. This occurs before the wheels of any of the cars following behind have arrived at the switch. Consequently, 25 the motor being uncoupled from the cars at about the time it passes the switch, it will be seen that the motor will continue to travel straight ahead on the rails 1 and 3, while the cars behind will be shunted off onto the 30 siding, thereby making what is commonly called a flying switch. It will be seen, though, that this is accomplished automatically and without any manual control over the switch.

In Fig. 6 a construction is shown which is 35 adapted to be used as a substitute for the bent portion 23 of the rod 19, and the roller 24, as a means for insuring the holding of the switch in either open or closed position. The construction shown in Fig. 6 comprises 40 a rod 27, which corresponds to the rod 19, and which is provided at its outer end with a weight 28, similar to the one previously described. The hand lever 29 is fulcrumed 45 at 30 on a plate 31 secured to the tie or sleeper. Said lever 29 is also pivoted at 32 on the rod 27, so that by this hand lever said rod can be reciprocated endwise. It will be seen, however, that the hand lever 29 50 tends to stay of its own accord in either position, and to resist any tendency of the rod to move endwise in the other direction. Consequently when the hand lever is in the position shown in full lines in Fig. 6, 55 the construction tends to hold the railroad switch in closed position; and vice versa, when the hand lever 29 is in the position shown in dotted lines in Fig. 6, the construction then tends to hold the switch in 60 open position.

The construction indicated at 7 and 8 65 may be of any suitable or ordinary character, such as that illustrated in Figs. 4 and 5, and being well known and understood, does not need description.

It will be seen that the construction shown and described is for operation by a train traveling in a direction to either take the side track or continue on the main track, and that the roller 15 is disposed in position 70 to be engaged and operated by a forward portion of the rolling stock, so that a rear portion will then travel by momentum onto the side track, having been uncoupled for this purpose, and the switch having been 75 automatically thrown or tripped in time to accomplish this particular switching operation.

What I claim as my invention is:—

1. In track construction, the combination 80 of a side track switch, mechanism for operating said switch, and means whereby said mechanism is automatically controlled by the rolling stock of a train traveling in a direction to either take the side track or continue on the main track, after a forward portion thereof has traveled on one track beyond the switch, so that an uncoupled rear portion of the rolling stock may continue by momentum and take the other 85 track, said mechanism comprising a lever pivoted on the road bed to swing in a horizontal plane, means to connect one end of said lever with the points of the switch, and means disposed on the other end of said lever in position to be operated by said portion 90 of the rolling stock which has passed the switch and thereby automatically throw the latter in time to accomplish said switching operation. 95

2. A structure as specified in claim 1, in combination with a safety device to hold the switch against movement when shifted to either position.

3. A structure as specified in claim 1, in 105 combination with a hand lever suitably connected with the switch, thereby to manually control the switch when such is necessary or desirable, and means tending to hold the switch in either position.

4. In track construction, the combination 110 of the main rails (1, 2 and 3), the movable switch points (5 and 6), the side track rails (9 and 10), a connection (11) between the switch points, a horizontally swinging lever (12) engaging said connection, a roller (15) on said lever, said roller and lever being disposed between the switch points, so that said roller is also between the other rails (1 and 10), and a cam plate (16) on the rear 120 end of the forward rolling stock to engage said roller, so that the rolling stock in rear thereof will take the side track, substantially as described.

5. In track construction, a side track 125 switch, an operating mechanism therefor including a hand lever, means including a horizontally disposed pivoted arm having a weight to prevent displacement of the switch after being shifted into either posi- 130

tion, and means whereby the arm is automatically shifted endwise by the rolling stock to throw the switch.

6. In track construction, the combination 5 of a side track switch, means including a rod connected to operate the switch, a hand lever connected to said rod, a weight on the outer end of said rod, and means whereby

the weight is automatically shifted by the rolling stock to throw the switch, said 10 weight resisting displacement of the switch from either position thereof, and said rod being movable endwise to permit operation of the switch.

Signed

IGNATIUS G. POSPYHALA.
